UNITED STATES PATENT OFFICE

148,724

DESIGN FOR A ROCKING ANIMAL FIGURE TOY

Joseph Nicholas Schauenberg, Toronto,
Ontario, Canada

Application October 18, 1946, Serial No. 134,036

Term of patent 3½ years

(Cl. D34—15)

To all whom it may concern:

Be it known that I, Joseph Nicholas Schauenberg, a citizen of Canada, residing in the city of Toronto, county of York, and Province of Ontario, Dominion of Canada, have invented a new, original, and ornamental Design for a Rocking Animal Figure Toy, of which the following is a specification, reference being had to the accompanying drawing, forming part thereof, wherein

Fig. 1 is a side elevation of the rocking animal figure toy, showing my new design,

Fig. 2 is a view in perspective above and at the rear, and

Fig. 3, a perspective view from the front thereof.

I claim:

The ornamental design for a rocking animal figure toy, as shown.

JOSEPH N. SCHAUENBERG.
